ORE CRUSHER

Edward Thomas Hamblin, Winnipeg, Manitoba,
CanadaApplication April 6, 1936, Serial No. 72,925
In Canada April 6, 1935

2 Claims.

(Cl. 83—9)

My invention relates to improvements in ore crushers and an object of my invention is to provide an ore crusher which will operate at high speed, and will occupy considerably less cubic space than the type of ore crusher at present in existence.

A further object of my invention is to provide an ore crusher having a cylindrical drum and a crushing wheel therewith, the ore drawn out 10 the side of the drum and being crushed between the drum and the crushing wheel.

A further object of my invention is to devise in an ore crusher of the class described, means whereby the crushing wheel within the cylinder 15 will always lie parallel with the cylinder walls and cannot be wedged out of alignment by lumps of refractory ore between the cylinder and the wheel.

A further object of my invention is to provide a device of the character herein described in 20 which the size of the crushed particles issuing from the machine can be varied while the machine is in operation.

A further object of my invention is to provide a device of the character herein described having 25 a separating chamber from which thoroughly ground particles are expelled while the heavier and coarser particles are returned to the machine for further crushing.

A further object of my invention is to provide 30 a mill of the class described in which there is practically no rubbing or grinding, crushing being effected by the ore passing between two smooth surfaces upon which a pressure is applied.

A further object of my invention is to provide 35 a high speed ore crushing mill in which there is no intermittent shocking or vibration set up by moving parts thereof.

A further object of my invention is to provide 40 a device of this character which is rugged in construction and cannot become easily out of order.

A further object of my invention is to provide 45 a device of this character which may be simply manufactured and will sell at a reasonable price.

With the above more important objects in view 50 and such other minor objects as may appear as the specification proceeds, my invention consists essentially in the arrangement and construction of parts all as hereinafter more particularly described, reference being had to the accompanying drawings, in which:—

Fig. 1 illustrates a side elevation of my crushing unit.

Fig. 2 is a plan view of the same with the revolving drum shown in section.

Fig. 3 is a rear elevational view of the same.

Fig. 4 illustrates a sectional view of the segregating chamber used in combination with this machine.

Fig. 5 is a diagrammatic illustration of the machine. 5

Fig. 6 is a sectional view taken on the line 6—6 Figure 2.

Fig. 7 is a sectional view taken on the line 7—7 Figure 2.

Fig. 8 illustrates a perspective view of one of the crushing shoes which compose part of the rotor. 10

Fig. 9 shows a segment of the core used in the rotor together with the compression rings for binding the rotor to the axle. 15

In the drawings like characters of reference indicate corresponding parts in the different figures.

This device consists of a bed 1 having upstanding parallel side walls 2 and mounted upon the forward end of these walls are a pair of heavy standards 3 which are attached to the bed by 20 means of bolts 4 or in any convenient manner. Upon the forward ends of the walls 2 are a pair of opposed adjustable bearings 5 which may be slid along the upper surface 6 of the wall and bolted in any desired position. A set screw 7 is 25 provided to allow these bearings to be conveniently adjusted. An axle 8 is mounted within the bearings and two flanged wheels 9 are attached intermediately between the bearings for a purpose presently to be explained. 30

Within the angle formed between the walls 2 and the standards 3 are two further bearings 10 carrying axles 11 upon which are mounted flanged wheels 12 similar to the above mentioned wheels 9. These latter bearings, it should be noted, are 35 not adjustable but are firmly attached to the frame of the device.

At the upper ends of the standards 3 is a further set of bearings 13 immediately above the bearings 10. These latter bearings are also adjustable along the surface 14 of the standard and may be located in the desired position by means of the set screw 15 and afterwards clamped firmly to the support by the bolts 16. An axle 17 similar to the aforementioned axles 8 and 11 is mounted 40 within the latter bearings and a pair of flanged wheels 18 are attached thereto in alignment with the wheels 9 and 12. 45

Mounted upon the flanged wheels 9 and 12 and bearing against the wheels 18 is a cylindrical drum 19 having a smooth inner periphery 20 and small encircling flanges 21 extend around the outer ends thereof. 50

Passing around the center of the drum is a ring 22, the outer surface 23 of which is provided 55

with a slightly arcuate configuration, this ring being designed to act as a belt track in a manner which will presently be described. In alignment with the flanged pulleys are two circular rails 24 which are designed to engage with the pulleys, the flanges of which maintain the drum in position.

At one end of the drum is an encircling curved flange 25 attached by means of bolts 26 to the smaller flange 21. The curved flange, it should be noted, is provided with an enlarged circular aperture, in the center thereof, the edges of which are turned inwardly as at 27.

Upon the other end of the drum is a circular trough 28 having an enlarged orifice 29 in the inner side thereof communicating with the inner chamber within the drum. A somewhat smaller aperture 30 is cut through the outer side of the trough and an encircling flared lip 31 is attached on the outer side of the trough adjacent the edge of the aperture. The outer periphery of this lip extends into an encircling hood 32, the edges of which are turned inwardly as shown most clearly in Fig. 2. The lower portion of this hood is provided with an outlet aperture 33 to which is attached a spout 34 for expelling material from the hood.

Extending transversely between the standards 3, I provide a heavy brace 35 having flanges 36 at either end thereof which are securely bolted to the standards. Also attached to the standards adjacent the ends of the brace 35 are a pair of bifurcated brackets 37 having orifices 38 therein to receive pins 39. Mounted upon these pins are a pair of laterally extending lever or rocker arms 40, the inner ends of which are forked as at 41 and intermesh as shown most clearly in Figure 6.

Threadably received within the center of a tapped orifice in the brace 35 is a horizontally extending shank 42 upon the outer end of which is keyed a hand wheel 43. Loosely mounted upon the shank 42 is a sleeve 44 having an integral annular portion 45 attached intermediately along the length thereof, from the outer surface of which extend a pair of opposed lugs 46. Short screws 47 extend through these lugs and into the sleeve 44 and freely rotatable rollers 48 are mounted upon the screws between the lugs and the sleeve.

The forked ends of the rocker arms 40 are designed to also pass between the lugs and the sleeve and to bear against rollers 48. A stout cushion spring 49 is interposed between the annular portion 45 and the hand wheel 43.

With this arrangement, it will be obvious that as the hand wheel is turned in a right hand direction, the shank will thread through the brace 35 and will compress the spring against the annular portion. This will in turn, through the rollers 48, bear against the forked ends of the rocker arms 40 and will cause them to move inwardly.

In order to lock the shank in any desired position, a locking nut 50 is provided on the inner end of the shank and is designed to bear against the side of the brace 35.

Extending upwardly from a recess 51 within the walls 2 of the frame, are a pair of opposed bearings 52 through which is passed a heavy shaft 53. Firmly attached to this shaft at either end are a pair of substantially vertical arms 54 which carry split bearings 55 adjacent the upper end thereof.

An upstanding lug 56 is integrally attached to the end of each arm and a flared orifice 57 is provided therein. A curved socket 58 is made adja-

cent the narrow end of the orifice 57, this socket being designed to receive a complementarily formed head 59 of a rod 60.

The forward end of each rod is threaded as at 61 and is received within one end of a bifurcated member 62, the other end of which passes on either side of one of the rocker arms 40 and is pivotally attached thereto by means of pins 63. A locking nut 64 is also mounted upon the threaded portion of the rod 60 to lock the device in any desired position.

Within the bearings 55, I mount a heavy axle 65 which extends eccentrically through the drum 18. Rigidly attached to this axle is the crushing wheel 66, the periphery of which is designed to bear against the inner surface 20 of the drum 19 and to revolve therewith.

This wheel consists of a core 67 composed of a plurality of triangular segments 68, each segment being positioned at an angle of 60° with each adjacent segment. These segments are provided with apertures 69 extending centrally therethrough, the central portion 70 of which is cylindrical in shape and flares outwardly at both sides as at 71. Into these flared portions are placed split rings 72, the outer surfaces of which are formed complementarily to the seatings with which they engage. When several of these segments have been placed side by side, long bolts 73 are passed through aligned orifices therein and the segments are clamped together at which time, the rings 72 are compressed and bind firmly against the axle 65.

Extending outwardly from each corner of each segment is an integral lug 73 and similar lugs 74 are bolted adjacent the lugs 73. Through each of the lugs 73 and 74 extend pins 75 and over these pins are passed the hooked inner ends 76 of radial arms 77 which extend inwardly from each of the crushing shoes 78 shown most clearly in Figure 8. Each shoe, it should be noted, is provided with slots.

Integrally attached to the inner surface of each shoe 78 is an arcuate section 79 having two inwardly disposed studs 80. Similar opposed studs 81 are provided on the outer surface of the segments 68 and springs 82 are interposed therebetween. Over each of the springs is placed a rubber sheath 83 to prevent sludge from interfering with the action of the springs when the device is in operation.

Mounted at the side of the machine, I provide a small centrifugal pump 84 having a pulley 85 for rotation thereof, the inlet side of the pump being designed to receive the end of the spout 34. A conduit 86 extends upwardly and across the machine to communicate ultimately with a sludge hopper 87. A tube 88 extends from the lower end of this hopper into a sleeve 89 which is flared at the lower end as at 90 within a segregating compartment 91 composed of a glass wall 92 to the upper end of which is attached a frusto-conical roof 93. A sleeve 94 extends upwardly from this roof and encircles the tube 88. It should be noted, however, that a space 95 is provided between the tube 88 and sleeve 94 into the upper end of which is inserted a bushing 96 held in position by set screws 97. A discharge tube 98 extends outwardly from the side of the sleeve 94.

Below the glass wall 92 is affixed an annular portion 99 having a downwardly converging inner surface 100. A frusto-conical member 101 is firmly riveted to the under side of the annular portion and is provided at the lower end thereof

with an outlet aperture 102. A water pipe 103 extends through the side of the frusto-conical member and is provided at the inner end thereof with a nozzle 104 which is designed to spray water issuing therefrom in an upward direction.

Within the segregating compartment is mounted a separating member 105 consisting of an upright conical portion 106 and an inverted conical portion 107 therebelow with an intervening cylindrical portion 108. A plurality of fins 109 protrude outwardly from the surface of the cone 106 and pass through the flared portion of the tube 89 to hold the member in position. Further fins 110 extend from the sides of the cone 107 and bear against the inner edge of the annular portion 89 to prevent vibration of the member when the device is in operation.

Mounted to one side of the crushing machine, is a raw ore hopper 111 from the lower end of which extends a feed pipe 112 which passes through the flange 25 and opens within the drum 19. A branch pipe 113 communicates with the feed pipe at a point immediately below the upper end thereof and extends upwardly to receive the product issuing through the outlet aperture 102 within the segregating member.

The construction of my improved type of ore crushing machine having been described, the mode of operation will now be presented.

A belt is passed around the outer periphery of the cylindrical drum and runs upon the track 23. This drum is now rotated from a source of power and the crushing wheel therewithin is also rotated due to the contact thereof with the inner periphery of the drum. Raw ore is placed in the hopper 111 and water is introduced through the pipe 103. The ore passes down the feed pipe and is mixed with the water issuing from the branch pipe 113, the mixture passing into the rotating drum. This process is continued until the machine is fully charged, at which time, there will be about three to four inches of water along the bottom of the drum. The ore sinks to the bottom of the water and as the drum revolves, is carried in the direction the drum runs, gradually forming a thick mass in the side of the drum where the crushing is being done.

When this mass becomes thick, it sticks to the drum wall and is carried under the shoes of the crushing wheel. When the ore is going between the crushing surface, the water is squeezed out of the ore into the spaces on and between the shoes, this allowing the ore to travel in a continuous stream up the drum wall.

After the crushing is done, the ore remains on the drum wall and not on the shoes as the speed of the crushing wheel throws it off. The crushed ore then travels around on the drum wall until it strikes the water. The fine particles are then picked up in the water and carried off in the discharge. The heavier particles that will not float, remain in the bottom of the water and are carried around the drum wall for further crushing.

When the mill has been in operation for a little while, the partly crushed ore and that being fed into the drum mixes in the form of a pump as shown in Figure 5, and in this way, becomes distributed over the interior surface of the drum. As the ore is not carried up immediately, it drops into the water, it has a slight rolling motion as it goes up the incline of the drum wall.

About one half the water on the opposite side

of the drum to that upon which the crushing is being done is practically free from heavy particles of ore and remains comparatively smooth with little or no splashing when sufficient water is being fed in.

I have shown the position of the crushing wheel assembly as having its longitudinal and horizontal axial plane occupying the same position as the horizontal longitudinal axial plane of the drum but this position can be changed to suit different conditions, it being possible to raise or lower the crushing wheel by changing the length of the rods 60. By my method of pulverizing, a comparatively fine grade of crushing can be effected without the necessity of screening.

As the drum is rotating, any hard particles such as iron ore which cannot be crushed by the wheel, will fall into the circular trough 28 and may be removed therefrom at various intervals.

In the event of crushing gold ore, this trough 20 may be filled with a quantity of mercury which will form an amalgam with any free gold coming in contact therewith.

The sludge carrying the finely powdered ore now passes through the aperture 30 and over the 25 lip 31 into the circular hood 32 from whence it passes down the spout 34. It should be noted that I have made the hood 32 to completely surround the lip in order to catch droplets which may be thrown from the lip due to the centrifugal force exerted thereupon by the rapidly rotating drum.

The sludge now passes into the centrifugal pump 84 and is urged upwardly through the conduit 86 to be admitted ultimately into the sludge 35 hopper 87. This mixture passes down the tube 88 and the flared tube 89. However, during this time, water is passing upwardly along the surface of the lower cone 107 and mixes with the sludge which passes down over the upper cone 106. 40 When the stream of incoming water is adjusted correctly, the lighter particles in the sludge are carried upwardly with the water and passes between the sleeve 94 and the tube 89 to be expelled through the discharge tube 98. The heavier particles in the sludge, however, sink through the incoming water and pass downwardly through the outlet aperture 102 to be mixed with the raw ore and introduced into the drum for further crushing.

It should be noted that each shoe of the crushing wheel is provided with separate cushion springs so that in the event of an extremely hard particle passing between the inner periphery of the rotating drum and the surface of the shoes, 55 instead of the whole wheel moving away from the surface of the drum, a single shoe will be compressed and the remainder of the wheel will continue to crush as efficiently as before.

Should, however, a large particle endeavour to 60 pass between the drum and the wheel and compress the springs under a shoe to the limit, the whole wheel will then move away from the inner surface of the drum by pulling upon the rods 60 and exerting pressure against the spring 49.

I have also provided against the event of a hard particle endeavouring to pass between one end of the crushing wheel and the inner periphery of the drum from twisting the wheel out of alignment for as soon as one of the rocker arms 40 70 exerts pressure against the rollers 48, the spring 49 is compressed somewhat and the second rocker arm follows up to keep in engagement with the rollers. Thus both rocker arms are always moved the same amount and the shaft of the crushing 75

wheel is maintained parallel to the longitudinal axis of the rotating drum.

With this arrangement, I have found that I can crush large quantities of ore in a very thorough and efficient manner, the device requiring only a minimum amount of power to operate.

Since various modifications can be made in the above invention, and many apparently widely different embodiments of same, made within the scope of the claims without departing from the spirit and scope thereof, it is intended that all matter contained in the accompanying specification shall be interpreted as illustrative only and not in a limiting sense and I desire only such limitations placed thereon as are specifically expressed in the accompanying claims.

What I claim as my invention is:—

1. Improvements in ore crushing machines comprising a framework, horizontally aligned pairs of rollers mounted thereon, a hollow drum rotatably mounted upon said rollers, a further pair of rollers in vertical alignment with one of said horizontally aligned pairs thereof, means for rotating said drum, said drum bearing against said vertically aligned pairs of rollers during rotation thereof, a crushing wheel mounted within said drum, pivoted arms carrying said wheel, means for adjusting the pressure of said wheel against the interior periphery of said drum comprising a pair of tension members attached to said arms, rocker arms secured to said members, spring means bearable against the ends of said

rocker arms, manually operable means for varying the pressure of said spring means against said rocker arms, a mercury trough secured to one end of said drum, said mercury trough having a flange, said flange protruding outwardly therefrom and a discharge hood encircling the edge of said flange, said edge being secured to said framework.

2. Improvements in ore crushing machines comprising a framework, rollers mounted thereon, a drum mounted upon said rollers, a belt receiving track extending around said drum, a mercury trough at one end of said drum, a discharge flange protruding outwardly therefrom, a hood encircling said flange, a crushing wheel within said drum, pivoted arms designed to carry said wheel, said wheel consisting of a core, a plurality of segmental crushing shoes spaced therefrom, spring means extending between said core and said shoes, means for limiting outward movement of said shoes from said core, and further means for adjusting the pressure of said wheel against the interior periphery of said drum comprising a pair of tension members attached to said pivoted arms, rocker arms secured to said tension members, spring means bearable against the ends of said rocker arms and manually operable means for adjusting the pressure of said last mentioned spring means against said rocker arms.

30

EDWARD THOS. HAMBLIN.
